UNITED STATES PATENT OFFICE.

WILLIAM PRADDEX, OF LAWRENCE, MASSACHUSETTS.

SPOON.

SPECIFICATION forming part of Letters Patent No. 294,910, dated March 11, 1884.

Application filed October 5, 1883. (No model.)

To all whom it may concern:

Be it known that I, WILLIAM PRADDEX, of Lawrence, in the county of Essex, State of Massachusetts, have invented a certain new and useful Improvement in Spoons, of which the following is a description sufficiently full, clear, and exact to enable any person skilled in the art or science to which said invention appertains to make and use the same, reference being had to the accompanying drawings, forming a part of this specification, in which—

Figure 1 is a top plan view of my improved spoon; Fig. 2, a side elevation of the same, and Fig. 3 a bottom plan view.

Like letters and figures of reference indicate corresponding parts in the different figures of the drawings.

My invention relates more especially to that class of spoons employed in making pies; and it consists in a novel construction and arrangement of parts, as hereinafter more fully set forth and claimed, by which a cheaper and more effective device of this character is produced than is now in ordinary use.

The nature and operation of the improvement will be readily understood by all conversant with such matters from the following explanation, its extreme simplicity rendering an elaborate description unnecessary.

In the drawings, A represents the bowl, and B the handle, of the spoon, these parts being constructed of wood, metal, or any other suitable materials.

Journalized horizontally in the outer end of the handle, on the pin x, there is a small spur wheel or pinion, C, for crimping or producing an ornamental edge around the crust of the pie.

Attached to the upper side of the handle at its outer end there is a plate, D, and to the opposite side a plate, E, the plate D being elongated to form the blade G, and the plate E elongated and bifurcated to form the fork H.

Projecting laterally from the body of the handle there is a long thin blade, J, preferably composed of tin or sheet metal, which, when the handle is made of wood, may be inserted in a slot formed therein, and secured by the

rivets m, and when composed of metal may be formed integral with the handle; or it may be attached thereto in any suitable manner. The blade J is designed for trimming the pie, the knife G for pricking the crust of apple and the fork H the crust of mince pies. They also serve as guides for the wheel C, being pressed against the edge of the plate in crimping the pie. The knife and fork project in opposite directions, and each stand at an angle of about sixty-five degrees to the longitudinal axial line of the spoon, or so that when the spoon is held by the handle and used for pricking the crust of the pie, the handle being elevated at an angle of about twenty-five degrees, the knife or fork, as the case may be, will stand in a vertical position. The blade J not only serves as a knife to trim the crust of the pie, but aids materially in keeping the spoon from turning when it is grasped in the hand for use.

Having thus explained my invention, what I claim is—

1. The spoon, substantially such as described, combined with the blade J, arranged substantially as and for the purpose set forth.

2. The spoon, substantially such as described, having the blade G, arranged substantially as and for the purpose specified.

3. The spoon, substantially such as described, combined with the fork H, arranged substantially as and for the purpose set forth.

4. In a spoon substantially such as described, the wheel C, journalized in the outer end of the handle B, in combination with the fork H, substantially as specified.

5. In a spoon substantially such as described, the wheel C, journalized in the outer end of the handle B, in combination with the fork H and blade G, substantially as set forth.

6. The improved pie-spoon herein described, the same consisting of the bowl A, handle B, knife J, wheel C, blade G, and fork H, constructed, combined, and arranged to operate substantially as specified.

WILLIAM PRADDEX.
